UNITED STATES PATENT OFFICE.

ABRAM D. EMERY, OF TAUNTON, MASSACHUSETTS, ASSIGNOR TO THE
UNIVERSAL LOOM COMPANY, OF NEW YORK, N. Y.

SHUTTLE STOP-MOTION FOR LOOMS.

SPECIFICATION forming part of Letters Patent No. 605,602, dated June 14, 1898.

Application filed February 20, 1897. Serial No. 624,884. (No model.)

To all whom it may concern:

Be it known that I, ABRAM D. EMERY, of Taunton, Massachusetts, have invented certain Improvements in Shuttle Stop-Motions for Looms, of which the following is a specification.

The several objects of the herein-described improvements are to automatically always bring the operative parts of a loom to rest in a prescribed position, if a shuttle fails to box properly, without any smash, and with the warp so extensively slackened that the warp-threads will not be broken even if the shuttle stops in the shed. These objects are accomplished by the employment of the spring-actuated progressively-acting stopping instrumentality which in my pending application, Serial No. 643,320, is shown, described, and claimed in combination with a plurality of stop-motions with common connections to said stopping instrumentality. The said stopping instrumentality is adapted to bring the operative parts of the loom to rest by its progressive action during a prescribed part of one revolution of the lay-driving shaft, and it is combined, in the present case, with a shuttle stop-motion which is brought into operation if the shuttle fails to box properly and which is so timed as to perform its functions of slackening the warp and concurrently tripping said stopping instrumentality into action at such predetermined stage in the revolution of the lay-driving shaft as will result in bringing the operative parts of the loom to rest just after the lay has commenced to re-cede from the beating-line.

The accompanying drawings, representing the shuttle-stop and warp-slacking devices and so much of the loom as is necessary to illustrate the modes of operation of said devices are as follows, to-wit:

Figure 1 is a transverse vertical section of a portion of the loom, showing the principal members of the shuttle-stop and warp-slacking devices in side elevation. Fig. 2 is a horizontal section taken through the plane indicated by the dotted line $x-x$ on Fig. 1, affording a top view of portions of the lay and the shuttle stop-motion. Fig. 3 is a front elevation of the parts shown in Fig. 2.

The drawings show portions of an upright

loom-frame composed in part of the standards A A' and the horizontal members B B'.

The driving-shaft C is provided with the driving-pulley C' and the loose pulley C². The position of the driving-belt is governed by the belt-shifter forks D D, affixed to the horizontal slide-bar D', having pivoted to its front end the hand-lever D². A collar D³, affixed to the slide-bar D', has attached to it the free end of a contracting spiral spring D⁴, the opposite end of which is secured to the girder B. When the loom is running normally, the driving-belt, as shown in Fig. 1, is retained in engagement with the driving-pulley C' by means of the trip-lever E, pivoted at the rear end to the frame of the loom and having near its forward end a shoulder E', which engages the collar D³. When the hand-lever D² is swung outward into the position in which it is represented in Fig. 1, the toe F, projecting laterally from its hub, engages a collar F', affixed to the upper end of the slide-rod F², and pulls the slide-rod F² upward, and thereby compresses the expanding spiral spring F³, which abuts at its upper end against the perforated bracket F⁴, through which the rod F² slides, and delivers its thrust against the collar F⁵, affixed to the lower end of the slide-rod F².

The collar F' on the upper end of the slide-rod F² has fastened to it the free end F⁶ of the brake-strap F⁷, which surrounds two-thirds or more of the periphery of the brake-wheel F⁸, affixed to the driving-shaft C, and has its opposite end F⁹ secured to the frame of the loom.

The stopping of the loom involves the lifting, either manually or otherwise, of the forward end of the trip-lever E. This disengages the shoulder E' from the collar D³, and thus releases the belt-shifter slide-bar D' to the action of the contracting spring D⁴. The spring D⁴ then pulls the slide-bar D' backward and shifts the belt to the loose pulley C² and at the same time swings backward the hand-lever D², swinging downward the toe F, and thereby releasing the brake-strap F⁷ to the influence of its actuating-spring F³. When the toe F is withdrawn from the collar F⁵, the brake-strap F⁷, being thus released, is tightened around the brake-wheel in part by the expansion of the spring F³ and in part by the

frictional influence upon the brake-strap of the periphery of the brake-wheel, which rotates, as indicated by the curved arrow on Fig. 3, in such direction as to make that frictional influence tend to pull the brake-strap away from its fixed end F⁹, and thus cause it to tighten itself upon the brake-wheel.

To stop the loom if the shuttle fails to box properly, each shuttle-box is provided with a movable cheek G, which works in a slot G', formed in the rear side wall of the box. The outer end of the cheek G is vertically pivoted to the lay, and its opposite end has affixed to it a finger G², adapted to be pressed upon by the screw G³, adjustably inserted through one of the crank-arms G⁴ of the rock-shaft G⁵. The rock-shaft G⁵, which is provided with bearings upon the rear wall of the lay, extends across from one shuttle-box to the other and has at each end a downwardly-extending crank-arm like the arm G⁴. (Shown in Fig. 1.)

A torsion-spring G⁶, surrounding the rock-shaft G⁵, has one of its ends affixed to the box G⁷, which affords one of the bearings for the rock-shaft and has its opposite end secured to the collar G⁸, which is secured to the rock-shaft by the set-screw G⁹. The torsional strain of the spring G⁶ tends to press the crank-arms against the finger of the cheek-pieces, and thus rock the free ends of the cheek-pieces into the path of the shuttle. So long as the shuttle boxes itself properly in either box it pushes out the cheek-piece G of the box in which it is seated, and thus rocks the rock-shaft G⁵ against the influence of its torsion-spring G⁶. A dagger II, rigidly secured to and projecting upwardly from the rock-shaft G⁵, is thus swung out of operative position. If the shuttle fails to reach its place in either of the boxes, the rock-shaft G⁵ is not rocked and the dagger II inclines so far backward that during the latter part of the upward excursion of the lay the upper end of the dagger II catches under the shoulder I on the free end of the lever J, the opposite end of which is loosely mounted upon a stud J', projecting laterally from a bracket secured to the loom-frame.

The lever J has pivotally connected with it the upper end of the adjustably-extensible link K, provided about midway of its length with the shoulder K', which, when the lever J is pushed upward by the dagger II, engages the pin K², projecting laterally from the trip-lever E, and thus lifts the trip-lever E out of engagement with the collar D³, and thereby trips the belt-shifter and brake into action and stops the loom by the time the lay has descended and the shed opened. An arm J², projecting upwardly from the lever J, is provided with an adjustable screw-bolt which, by bearing against the girder B', serves as a stop to limit the range of downward movement of the lever J.

The link K is composed of two pieces K³ and K⁴, overlapped at their meeting ends and secured in a trough-shaped clamping-plate

K⁵ by the transverse screw-bolts K⁶. One or the other of the overlapped portions is provided with a slot K⁷ to permit the passage of the screw-bolt K⁶ and afford opportunity for varying the total length of the link K, as may be required. The lower extremity of the link K is pivoted to the crank-arm K⁸, affixed to the rock-shaft K⁹. The rock-shaft K⁹ is provided with two radially-projecting sears L L, one of which is shown in elevation in Fig. 1 in solid lines in the position which the sears occupy when the loom is running normally, in which position each sear engages the rear extremity L' of the adjacent side members L² of the rocking frame L³. The said frame is composed of two parallel arms L², extending transversely across and affixed to the rock-shaft M. The forward ends of the arms L² afford the bearings for the whip-roller L⁴.

When the loom is running normally, the warp N, maintained under proper tension, extends upward from the warp-beam N' over the whip-roller L⁴, thence under the fluff-catcher trough N², thence upwardly across the lease-rods N³, through the harnesses N⁴, and through the reed N⁵ to the weaving-line of the fabric in process of being woven; but if a shuttle fails to box properly the resulting upward movement of the link K causes the sears L L to be rocked out of engagement with the side members L² of the rocking whip-roller frame L³, which frame thereupon drops from the position in which it is represented in solid lines in Fig. 1 to the position in which it is represented in dotted lines in said figure. This so greatly slacks the warp that there will be no breaking of the warp-threads even if the shuttle should be in the shed while the beat is taking place, and a second beat cannot take place, because the self-tightening brake-strap is so effective that it is capable of stopping the loom during the one-half of one revolution of the lay-driving shaft ensuing next after the dagger II commences to lift the lever J.

What is claimed as the invention is—

1. In a loom, the combination, as herein set forth, of a progressively-acting stopping instrumentality adapted to stop the loom by its progressive action during a prescribed part of one revolution of the lay-driving shaft; a shuttle stop-motion adapted to be brought into operation during the latter part of the beating stroke of the lay, warp-slacking mechanism controlled by the said shuttle stop-motion, and connections between said shuttle stop-motion and said progressively-acting stopping instrumentality, whereby, if the shuttle fails to box properly, the operative parts of the loom are brought to rest just after the lay has commenced to recede from the beating-line.

2. In a loom, the combination, as herein set forth, of a progressively-acting stopping instrumentality adapted to stop the loom by its progressive action during a prescribed part of one revolution of the lay-driving shaft; a

shuttle stop-motion adapted to be brought into operation during the latter part of the beating stroke of the lay; a whip-roller for normally holding the warp under suitable tension; connections between said whip-roller and said shuttle stop-motion and connections between said shuttle stop-motion and said progressively-acting stopping instrumental-
5 ity, whereby, if the shuttle fails to box prop-

erly, the warp is slackened and the operative parts of the loom are brought to rest just after the lay has commenced to recede from the beating-line.
